CLAIM

The ornamental design for a laundry cart as shown and described.

DESCRIPTION

FIG. 1 is a front elevation view of a laundry cart, showing our new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a bottom perspective view thereof;

FIG. 8 is a top perspective view thereof; and,

FIG. 9 is a further perspective view thereof with a flip top in a closed configuration.

The cross hatch shading in the figures is fragmentarily shown for convenience, it being understood that the cross hatch shading is uniformly applied over the surface on which it appears.
